BALING PRESS

Thaddeus S. Grimes, Columbus, Ga., assignor to
 The Lummus Cotton Gin Company, Columbus,
 Ga., a corporation of Georgia

Application September 10, 1930, Serial No. 480,996

15 Claims. (Cl. 100—28)

My invention relates to improvements in presses for baling cotton and other material.

Briefly stated, my invention has for one of its primary objects to provide novel mounting means

5 for the hydraulic cylinder head whereby to reduce the height of the press; obviate the necessity of locating the press-sills at a level below the floor of the gin room; and also to provide a compact, sturdy, and highly efficient cylinder head
 10 mount which is of great advantage over prior constructions from the point of view of economy, both in installation and maintenance.

More specifically,—it is an object of the invention to locate the hydraulic cylinder head in supported relationship between the sills of the press,—thus, doing away entirely with the necessity for an expensive mount for the cylinder head above the sills which in addition to increasing the cost of the installation is apt to,—and frequently 20 does,—work loose and require attention.

A further specific object of the invention is to provide novel reinforcing means for the I-beam sills which carry the hydraulic cylinder head.

The invention also resides in the provision of a 25 novel bale-box extension mounted for limited linear movement under the action of the ram as it compresses the cotton whereby to prevent warping of the press and loosening of the press frame after considerable use.

30 Another object of the invention is to provide in a baling press, bale-confining doors mounted for limited sliding movement in the direction of movement of the ram when compressing the cotton,—there being means associated with the doors 35 for holding same against such movement when the cotton or other material is being tramped into the press.

More specifically,—it is an object of the invention to provide in a cotton press a ram actuated 40 follow block for compressing the cotton, doors slidable in the direction of movement of the ram and means actuated by said follow block when the cotton is being tramped into the press to hold said doors against sliding movement, of which 45 they would otherwise partake because of the lateral pressure of the cotton against the doors and the lifting pressure of the cotton against the dogs which are carried by the doors.

A still further object of the invention is to provide means for tying the side and end doors together whereby they will move as a unit under the action of the ram when compressing the cotton.

Still another object of the invention is to provide novel end doors extending the full height of

the press whereby to give more room between the end door and a bale of cotton at the bottom of the latter to facilitate wrapping of bagging around the bale.

Additionally the invention contemplates end doors for the baling press extending the full height of the press and which are floatably supported for limited vertical movement whereby to obviate any warping or loosening strain upon the press frame.

An additional object of the invention is to provide in a baling press, end doors extending the full height of the press and side doors of relatively shorter height, both end and side doors being floatably supported for limited movement 15 in the direction of movement of the baling ram, and there being means for tying said doors together whereby they will move as a unit,—the great length of the end doors tending to keep the press in shape and the side doors in proper 20 squared and aligned relationship with the side walls of the press which will greatly increase the life of the press and the period of use without mechanical attention.

The invention also resides in certain novel 25 features of construction, combination and arrangement of the various parts and in certain modes of operation,—all of which will be readily understood and appreciated by those skilled in the art upon reference to the accompanying 30 drawings in connection with the detailed description appearing hereinafter.

In the drawings wherein the same reference characters have been used to designate the same parts in all views,

Figure 1 is a side elevational view illustrating a two-story double box cotton press incorporating my invention;

Figure 2 is an end elevational view of the same; 40 Figure 3 is a perspective view of one of the short end doors incorporated in the press;

Figure 4 is a perspective view of the follow block-actuated hold down means for the short end doors when the tamper is in action;

Figure 5 is a perspective view of the press; 45

Figure 6 is a view partly in end elevation and partly in section showing the hydraulic cylinder head supported by the sills of the press;

Figure 7 is a perspective view of one of the sill reinforcing devices;

Figures 8 and 9 are detail views partly in elevation and partly in section showing the door clamp-means which is carried by the side doors;

Figure 10 is an end elevational view of a different form of press incorporating the invention;

Figure 11 is a fragmentary side elevational view of the device of Figure 8, and

Figure 12 is a perspective view of a bearing element providing side recesses permitting the long end doors to swing open.

Figure 13 is a detail sectional view taken on the line 13—13 of Figure 1 showing the means for floatingly supporting one of the long end doors 50.

Referring specifically to the drawings, and particularly to Figure 5,—1 designates the floor of the gin room upon which is mounted the ginning machinery 2 and in which is dug the hole 3 to receive the cylinder 4 of the hydraulic ram or piston 5 whose head 6 is secured between, and supported by, the sills 7 (see Figure 6).

As best shown in Figures 1, 2, and 6, the cylinder head 6 has its ends and bottom formed as at 6a to engage the web of the I-beam sills 7 and to rest upon the base flanges thereof.

20 The cylinder head cap 6b, as shown in Figure 6, is bolted in place by means of bolts 6c.

25 Tie rods 9 extend through the enlarged bearing portions of brace bars 8 to tie the rails together,—the base bars 8 exactly conforming to the outer web and flange portions of the rails 7 whereby to prevent twisting of the rails under the action of the ram 5 working through head 6.

30 This provides a very light construction and the brace members 8 effectually reinforce the I-beam sills.

35 The tie rods 9 serve to effectually clamp the I-beams or sills to the cylinder head to hold the same against movement,—it being understood that the ram goes through the cylinder head without resistance.

40 Suitable cross members 11 connecting the sills 7 at their ends carry the vertical rods 12 of which there are two at each end of the sills. One pair of rods 12 supports the cross member 13a carrying the sills 13 which support the trumper mechanism shown in Figures 1 and 2, but which forms no part of the present invention, although designated as 28 for purposes of convenience and reference.

45 The other two rods 12 support the I-beams 14 through a cross member 14a, and suitable supports 15 carried by the I-beams 14 support the inner end of the trumper carrying beams 13, previously referred to.

50 Suitably secured between the I-beam sills 7 and intermediate their ends, is the bearing or support 16 for the column 17. The duplicate press boxes 19, 20 are swingably supported on this column 17 by means of bearings 18, 18b, and it is here to be observed that the press boxes 19, 20, are connected by the substantially circular platform 32, the outer portion of which is supported by props or braces 33, as best shown in Figure 2.

55 The press itself is of familiar type. The tramper 28 feeds the cotton into the box 19, as shown in Figure 1. While this is going on, the ram 5 is acting upon the follow block 47 in the other press box 20 for compressing the cotton upwardly toward the head block 14b carried by the I-beams 14. The follower block 47 forms the bottom of the press box. The tramper will fill the box with cotton substantially up to the top. The follower block 47, under the influence of the ram 5, compresses the cotton into the upper end of the box which is formed, as clearly shown, by the door members which will be referred to in detail later on.

60 The press boxes 19, 20, have extensions including side doors 21, 22, respectively which have secured thereto the I-beams 21a, 22a, respectively

that provide the bearings 21b, 22b, respectively. These bearings 21b, 22b swingably mount the doors 21, 22 upon vertical side shafts 23, which are connected by short channel bars 24 supported by collars 26a on the shafts 23 (see Figure 1) whereby to maintain the doors 21, 22, at a desired elevation,—it being customary to leave a space of approximately $\frac{3}{4}$ of an inch between the top of the side doors and the head block 14b so as to permit bagging to be disposed around the bale B, indicated by dotted lines in the press box 26 in Figure 1.

65 The I-beams 21a, 22a of the doors also extend beyond the outer end portions of the press box, as shown in Figure 1, and are provided with means, which will be referred to later on, for confining the elongated outer end doors securely in place.

At this point particular attention is called to the fact that the channel bars 24 support the bearing portions 21b, 22b so that there will be approximately a 1" (one inch) space 25 therebetween permitting the side doors 21, 22 to slide a limited distance vertically on the rods 23. This space 25, with the $\frac{3}{4}$ inch spacing between the upper door ends and head block 14b, becomes very important in the practical operation of the press, since, it avoids any possibility of warping of the press or loosening of the press frame, which has proven very objectionable in prior presses wherein the doors have been hinged at their lower ends to the press boxes. Since the space 25 between the bearing portions 21b, 22b is greater than the spacing between the top ends of doors 21, 22 and head block 14b, there will be no warping through contact between bearings 21b, 22b. As will be mentioned later on, the end doors 50 and 40 have their upper ends normally spaced about $\frac{3}{4}$ of an inch from head block 14b and are also capable of limited vertical sliding movement. As will be pointed out later on, the doors of each box are bound together so that they will be held rigidly assembled whether partaking of limited sliding movement or held stationary.

70 The bearings or supporting rods 23, which carry the side doors 21, 22, are suitably supported in the frame-work connecting the press boxes.

The side doors 21, 22, as usual, carry the dogs 30 which extend into the press box and which will be supported as indicated at 29. Diagonal tie rods 31 connecting I-beams of the doors serve 50 to reinforce the construction of said side doors 21, 22.

75 The I-beams 21a, 22a, of the side doors, 21, 22, respectively, extend beyond the outer ends of the doors, as previously intimated for carrying locking means. The bracing of platform 32 by braces 33 is customary construction.

80 Relatively short doors 40 may be provided at the ends of the press boxes 19, 20 as are shown in association with the side doors 21 in Figure 1. These doors 40 are exact duplicates and therefore a description of one will serve for both.

85 Referring to Figures 1 and 3, the lower ends of the end doors 40 normally rest upon the end walls of the press box proper and their bottom edges extend slightly below the channel bars 18a secured to the end walls of press box 19.

90 Each door 40 carries, adjacent its lower end, a bearing 43 straddling the slot 41 which is formed by the two sections of the door which are connected by diagonal I-beams 42.

95 The bearing 43 is bolted to the door 40, as indicated at 44.

100 In order to prevent the end doors 40 from being moved upwardly when the trumper is in

action, by reason of the transverse pressure of the cotton against the inner surfaces of such end doors 40.—I provide the elongated rod 45 having the hooked end 45a extending through the bearing 43 which, as shown, has a vertically elongated hole 43a. The lower end of the rod 45 is threaded, as at 45b, and extends through an angle bracket 46 which is bored, as at 46a, to receive the end of said rod.

10 Suitable nuts 45c on the rod 45 enable the angle bracket 46 to be adjusted so as to hold the end doors 40 down upon the upper ends of the box walls through the action of the follow block 47 in the position shown in Figure 1, wherein it 15 rests upon and engages the angle brackets 46, whereby to hold the end doors 40 in the position shown and described. However, when the follow block 47 is pushed upwardly by the ram 5 it will be obvious that the doors 40 will be free to 20 move upward against the head block 14b carried by the upper sill members 14.

In lieu of the short doors 40 I may use, at the outer ends of the press boxes, the elongated end doors 50 as shown applied to press box 20. The 25 platform 32 is cut away so as to permit the end doors 50 to extend the full height of the press so as to provide a closure for the outer ends of the press box proper, and also for the ends of the bale receiving portion of the press box between side 30 doors 22.

The I-beams 21a, 22a, of the side doors 21, 22, carry at their inner and outer ends tie or clamp means which is preferably of the type generally designated as at C on I-beams 22a (Figure 1). 35 This means C serves to bind all of the doors of each box together as a unit and, as has been pointed out, the doors are free to move as a unit upwardly about one inch (1") which is the distance indicated at 25 in Figure 1 between the 40 bearing portions 21b, 22b and their supports 24.

The construction described eliminates entirely 45 any possibility of warping or straining the press. When the ram 5 is actuating the follow block 47 through the lower portion of the press box below the platform there is no substantial strain because the cotton has not been sufficiently pressed to exert a strain. However, when the follow block 47 has been actuated up into the upper part of the press which is defined by the doors hereinbefore referred to, the pressure becomes quite great, that is to say, the lateral pressure of the cotton. In fact, under the action of the ram upon the 50 follow block 47 the doors have a tendency to go upward. I have already pointed out the necessity of leaving a space at the top of the doors to permit bagging to be inserted for the wrapping of the bale B. Therefore, when the ram is operated the doors of each box will be jammed up against the head block 14b, and there will be no strain on the press as would be the case were the doors pivoted at their lower ends to the press 55 itself.

The elongated end doors 50 are permitted to move up with the side doors 22, since their lower 60 ends are floatingly supported between the cross members 52, 52a at each end of the press box 20 near its bottom as shown in Figures 1 and 13. Each door 50 has an outwardly extending flange portion 51 adapted to rest upon one cross member 70 52, while there is provided at the inner surface of the door 50 adjacent its lower end and below the plane of the member 51, an angle bracket plate 51a which is adapted to be disposed beneath the lower surface of one end of the follower block 47. 75 Manifestly, when the block 47 is in the position

shown in Figure 1, the end doors 50 will be held from upward movement,—which is to say while the ram 5 is in action. However, when the ram 5 is actuated against the follower block 47 to press the same upwardly in the press box, the doors 50 with side doors 22 will be manifestly permitted to slide upwardly the aforementioned three fourths of an inch (3/4"). to engage the head block 14b, and this without the binding of bearings 21b, 22b against one another or channel bars 24 since space 25 is one inch (1") or more. It is to be remembered, as previously pointed out, that all the doors of each press box are bound together by the clamp means C carried at each end of the I-beams 21a, 22a of the side doors, although deleted for the sake of clarity except at the outer ends of I-beams 21a and 21a.

Each clamping means C includes a vertical shaft 64 having cam ends 67 acting upon tie means carried by the projecting I-beams of the opposite side door and upon the I-beams of end doors 50 or 40 for binding the whole together as a unit. The rod 64 is actuated by the lever member 68, the end of which will normally be engaged by a hook 69 to hold the cam portions 67 in operative position. The lever 68 is simply thrown outwardly when it is desired to release the doors to remove a bale from the press box.

In Figures 10 and 11 there is shown a single box press incorporating sills 1'; cylinder head 6'; sill braces 8'; tie rods 9'; a press box 19' having elongated end doors 50' and side doors 21' whose frame bars 22' are hinged as at 18' to suitable upright frame carried shafts 17'.

Here the follower block 47' engages cleats 53' of 35 doors 50' to hold same down,—said doors having supporting cleats 51' at the opposite side adapted to rest on cross member 52'. Guides 70' slidingly confine the lower end of each door 50' as per Figure 11.

The bars 22' of side doors 19' have the usual 40 clamp means (not shown) for clamping doors 21', 50' together for limited vertical movement under the action of block 47' so that their upper ends will bear against the head block 14'.

As will be seen the construction involves the same principles as in the double box press of Figures 1 and 2, there being a normal space (25') of an inch (1") or more between the bearing stops 24' and frame bar bearings 18' on shafts 17' 50 whereas the space between the upper ends of the doors 50', 22' and the head block 14' will be only about three quarters of an inch (3/4").

Having thus described my invention, what I claim as new and desire to secure by Letters Patent is:

1. In a baling press having a ram, and a head through which said ram works, a pair of spaced supporting sills for said press and having opposed lateral seat portions supporting said head, tie means binding said sills together and against the sides of said head to hold the latter upon said seat portions, and reinforcing means for said sills and held in place by said tie means.

2. In a cotton press, supporting I-beam sills 65 therefor and resting upon the gin room floor at substantially the gin base level, a ram cylinder head between said sills and supported upon the opposed base flanges thereof, the sides of said cylinder head being shaped to engage the web 70 portion of said I-beam sills, tie rods extending through the web portions of said sills for binding the latter against said head to hold the same in place, reinforcing braces adapted to seat against the web and flange portions of the I-beam at the 75

outer surfaces thereof whereby to prevent twisting of the same, and said reinforcing braces being held in place by said tie rods.

3. In a cotton press having a press box, the combination of a ram, a head block associated with said press and toward which said ram is adapted to move to compress the contents of the box, outwardly movable doors providing a walled bale receiving extension of said box and movable relatively of the press box proper toward and against the head block, means for tying said doors together, at least one of said doors being elongated with respect to the others and providing a side closure for the press box proper, press box means for supporting said door for sliding and outward swinging movement, and the outer ends of said doors being normally spaced short of the plane of said head block and movable thereagainst under the action of the ram upon the work.

4. In a cotton press having a press box, the combination of a ram, a head block associated with said press and toward which said ram is adapted to move to compress the contents of the box, said box having a walled bale receiving extension movable relatively of the press box proper toward and against the head block, the outer end of said extension being normally spaced short of the plane of said head block and movable thereagainst under the action of the ram upon the work, a door incorporated in said bale-receiving extension, and means carried by said door for holding said press box extension out of plane with said head block when the ram is in inoperative position.

5. In a cotton press having a press box, the combination of a ram, a head block associated with said press and toward which said ram is adapted to move to compress the contents of the box, outwardly movable doors providing a walled bale receiving extension of said box, and movable relatively of the press box proper toward and against the head block, the outer ends of said doors being normally spaced short of the plane of said head block and movable thereagainst under the action of the ram upon the work, and means carried by one of said doors for holding said press box extension out of plane with said head block when the ram is in inoperative position.

6. In a cotton press having a press box and supporting sills therefor, the combination of a ram, a head block associated with said press and toward which said ram is adapted to move to press the contents of the box, and said press box having a relatively movable bale-receiving extension normally spaced short of the plane of said head block and movable thereagainst under the action of the ram upon the work, and press box-extension-carried means adapted to be engaged by said ram for holding said extension spaced from the plane of said head block when the ram is in inoperative position.

7. A baling press comprising a base, press boxes mounted on said base and connected together in spaced relationship, there being separate ram and trumper means with which the respective press boxes are adapted to be selectively registered, the upper end of each box having a relatively movable extension adapted for actuation against an abutment in the compressing movement of the ram, said extension comprising in each instance a pair of swingable and slideable side doors, outer end doors, inner end doors, certain of said end doors providing end closures for a press box proper, means for tying all of said

doors of each box extension together for movement as a unit under the influence of said ram, and hold down means associated with certain of said doors for holding the same against ram direction movement when the trumper is in action.

8. The combination set forth in claim 7, and means associated with said ram and constituting an element of said hold down means.

9. In a cotton press having a press box and a ram movable into said press box, a head block carried by the press and toward which said ram moves to compress the contents of the box, outwardly movable and vertically pivoted doors providing a walled bale receiving extension of said box, means for tying the said doors together, the upper ends of said doors being normally spaced short of the plane of said head block and movable thereagainst under the action of the ram upon the work, and connections between certain of said doors and the ram to restore said doors to normal position upon reverse movement of the ram.

10. In a press, a press box proper, a head block, a plurality of outwardly swinging doors providing a bale-receiving extension at one end of said press box proper and movable relatively of same toward and from said head block, means for securing said doors together, guide means for guiding said extension in its movement toward and from said head block, and portions of said guide means cooperating with certain doors to provide pivots therefor substantially transversely of the axis of the press box proper, one of said last mentioned doors being elongated and providing a closure for one side of the press box proper.

11. In a cotton press, a press box, a head block spaced thereabove, a press box extension disposed for vertical movement between said box and head block to engage the block, means operable through said press box to compress cotton into said extension and against the head block, and means cooperatively associated with said compressing means and the press box extension to hold said extension against vertical movement toward said head block prior to activation of the compressing means.

12. In a baling press providing a press box proper and a bale box extension, the combination of an elongated end door providing a wall for corresponding areas of both the bale box extension and the press box proper.

13. In a baling press providing a press box proper and a bale box as an extension of the press box, said bale box comprising outwardly opening side and end doors for admitting of drawing bagging about a bale and removal of the bale from the bale box, at least one of said bale box doors being elongated to provide an inner end portion overlying the press box proper and providing at least a substantial portion of a wall of the press box proper, and cooperating means carried by said press box and inner end portion of said elongated door at a point remote from said bale box for swingably supporting said elongated door transversely of the axis of the press for outward movement whereby when such long door is open to leave exposed between the door and a bale in the bale box a wide space to admit of easy bagging of the bale.

14. In a baling press providing a press box proper and a bale box extension, there being vertically pivoted doors providing two opposed walls of said bale box; the combination of elongated doors providing two other opposed walls

of said bale box and corresponding wall portions of said press box, and press box carried means remote from the bale box providing a horizontal pivot support for said elongated doors.

5 15. In a baling press providing a press box proper and a bale box extension, the combination of an elongated end door providing a wall

for corresponding areas of both the bale box extension and the press box proper, and means carried by the press box remote from the bale box and supporting said elongated door for outward swinging movement transversely of the axis of the press. ⁵

THADDEUS S. GRIMES.
